CAR COUPLER

George T. Johnson and Harry H. Wolfe, Columbus, Ohio, assignors to The Buckeye Steel Castings Company, Columbus, Ohio

Application October 26, 1934, Serial No. 750,186

1 Claim. (Cl. 213—155)

This invention relates to improvements in car couplers, and more particularly to a novel car coupler knuckle for the A. R. A. standard "E" coupler.

One of the objects of the invention is to so design a car coupler knuckle as to facilitate manufacturing practice and increase the efficiency of operation of the knuckle when it is assembled in the coupler head.

Knuckles of the usual construction are for the most part what is termed "chunky" castings, or castings that are nearly a solid mass of metal. Due to this prior construction, the finished castings often contained hidden defects because of the heavy sections and mass of metal. These defects are caused by internal shrinks or drawing of the metal and the pocketing of gas by the heavy mass of metal. Furthermore, as such knuckles are relatively heavy, they are difficult to operate, that is, open or close, when in service and assembled in a coupler.

Therefore, another object of the invention is to construct a knuckle of superior design which will greatly improve the manufacturing process and the serviceability of the knuckle.

A further object is to increase the efficiency of operation when the knuckle is in service and assembled in a coupler, and this is accomplished by providing a light weight knuckle of improved design requiring less effort to open and close.

A still further object is to minimize the cost of manufacture of a car coupler knuckle by using considerably less metal than is ordinarily used in making a conventional knuckle.

A further purpose is to make a knuckle of equal or greater strength, but of less weight than the conventional knuckle.

With the foregoing objects outlined and with other objects in view which will appear as the description proceeds, the invention consists in the novel features hereinafter described in detail, illustrated in the accompanying drawings, and more particularly pointed out in the appended claim.

45 In the drawings,

Fig. 1 is a side elevation of the improved knuckle viewed from the pulling horn side.

Fig. 2 is a rear elevation.

Fig. 3 is a top plan view of the improved 50 knuckle.

Fig. 4 is a bottom plan view of a portion of the knuckle.

Figs. 5, 6, 7, 8 and 9 are sections taken respectively on the lines 5—5, 6—6, 7—7, 8—8 and 9—9 55 of Fig. 3.

Referring to the drawings, the knuckle 10 comprises principally the pulling horn 11, the hub 12 and the tail 13, the latter including top and bottom pulling lugs 14 and 15, a lock support 16, and a locking face 17. Buffing shoulders 18 and 18a are positioned on the tail between the hub and the pulling lugs. A pivot pin aperture 19 extends through the hub.

The usual practice has been to cast the above component parts of a knuckle as a solid casting, except for the pivot pin opening and a small lightening opening within the horn 11. This practice often results in hidden defects in the casting, due to abrupt changes in the mass of the metal in various parts of the mold, which cause internal shrinks and pocketing of gases.

In accordance with our invention, the casting is skeletonized and the exterior is so designed that abrupt changes in metal sections and mass are avoided, whereby the quality of the casting is improved. In keeping with our invention, the knuckle, at the place where the tail merges into the hub, is provided with upper and lower cavities 20 and 21 which communicate with the pivot aperture 19 and extend rearwardly into the tail.

To support the pivot pin against bending, a shoulder or apertured web 22 is positioned between said cavities, and obviously, this shoulder will surround the pivot pin (not shown) when the knuckle is assembled in the coupler housing.

A vertical aperture 23 is formed in the tail between the cavities and the pulling lugs 14 and 15, and produces a more desirable uniform rate of cooling for the various component parts of this portion of the knuckle during the casting operation.

The rear end of the tail has also been lightened by providing it with upper and lower recesses 24 and 25 positioned at the rear of the pulling lugs. This design reduces the mass of metal at these locations, thereby speeding the cooling of the metal in the mold, so that all parts of the knuckle will cool at substantially the same rate.

Likewise, the structure of the lightening hole 26 commonly found in the pulling horn of this type of knuckle has been modified so as to provide upper and lower cavities 27 and 28 which extend from the hole 26 toward the hub of the knuckle. These cavities, in addition to lightening the knuckle, have the function of making the metal mass in that portion of the knuckle substantially uniform, so that the cooling rate is similar to other portions of the knuckle.

Insofar as the lightening cavities, recesses, and apertures are concerned, it will be observed that

they are rounded, or of such shape that abrupt changes in the metal sections are avoided, thereby removing the cause of internal shrinks, blows and draws, all of which cause defects in the finished casting.

We prefer to make the knuckle of a cast steel possessing certain physical properties; i. e., ultimate strength, yield point, elongation, and reduction of area, which justify the use of a higher working fiber stress in carrying out the invention. High grades of steel are obtained by using alloys such as manganese-vanadium, manganese-molybdenum, etc., with certain heat treatments after the metal is cast. However, we do not wish to be limited to any particular alloy of steel or form of heat treatment.

While we have disclosed a preferred embodiment of the invention and stated desired metals to be employed, it will be understood that various changes may be made in such disclosures, without departing from the spirit of the invention, as expressed in the claim.

What is claimed and desired to be secured by Letters Patent is:

A substantially hollow car coupler knuckle comprising a hub, pulling horn and tail integrally united to form a unitary structure, said knuckle having upper and lower buffing shoulders and upper and lower pulling lugs positioned rearwardly of the hub, the tail being provided with a substantially vertically disposed aperture positioned between the shoulders and lugs and with top and bottom recesses positioned rearwardly of the lugs, said horn being provided with a vertically disposed aperture and with horizontally disposed cavities which merge into the last mentioned aperture and extend from the latter toward the hub, said hub having a vertical pivot pin aperture and rearwardly projecting cavities which are segregated from the horn cavities and merge into the pivot pin aperture, said apertures and cavities being arranged to provide a substantially uniform metal thickness throughout the knuckle and none of said cavities being visible from any side of the knuckle.
